UNITED STATES PATENT OFFICE.

IRA E. McCABE, OF CHICAGO, ILLINOIS.

PRESSURE-ACTUATED ELECTRIC CONTROL DEVICE.

Application filed November 9, 1925. Serial No. 67,796.

This invention relates to improvements in electric control devices and more particularly to a pressure actuated electrical control device.

5 In many instances electrically operated devices are employed in the production of heat and in the electric circuit of such a device it is desirable to provide a control for starting and stopping the operation of such a device 10 which control is operated by the temperature created by the operation of the device.

It is an object of this invention to provide a device of this character, and an embodiment of this device is particularly illustrated 15 and described as adapted for use in an electrically operated furnace or heat producing device particularly used as a part of an electrically operated liquid fuel burner system for domestic purposes, although this invention contemplates other uses of this control. 20 It is a further object to provide a device of this character which is particularly adapted in electrically operated domestic liquid fuel burner systems to act as a safety device for 25 such systems.

While a preferred form of this invention is illustrated on the accompanying sheet of drawing, yet it is to be understood that minor detail changes may be made therein 30 without detracting from the scope of the invention.

In the drawings:

Figure 1 is a view in front elevation of a preferred form of this device, with the casting cover removed and partly in section.

Figure 2 is a view in end elevation of Figure 1 with parts broken away and with parts in section.

In the embodiment of this invention illustrated, the circuit to the motor is closed or 40 opened by the tilting movement of the mercury switch 1, which is shown mounted on a pivoted carrier plate 2, with two terminals adjacent each other and near one end of the tube so that when the tube is tilted in that 45 direction the mercury within the tube will accumulate in that end and close the circuit through said terminals, and when tilted in the opposite direction the mercury will flow 50 away from the terminals and break the circuit therethrough. The tilting plate carrying the mercury tube is provided with a counterweight 3 which will normally tilt the tube to the open or circuit-breaking position. 55 The plate 2 carrying the mercury tube is also provided with a depending projection in the

form of a pawl 4, adapted to engage in the teeth of a ratchet wheel 5 carried by a sleeve 6, having a detachable connection with an enclosed fixed shaft 7, whereby the mercury tube switch may be tilted into the closed position and held against the counterweight by engagement of the pawl with the ratchet and which when the ratchet carrying sleeve becomes detached will allow the counterweight to cause the ratchet to be rotated by the pawl releasing the tilting plate 2 and tilt the switch into the open position.

The sleeve 6, carrying the ratchet wheel 5, is of greater inner diameter than the outer diameter of the fixed shaft 7, which it surrounds. The space between the inner circumference of the sleeve and the outer circumference of the shaft is filled with solder which will normally secure the sleeve in 70 fixed position on the shaft. The shaft 7, is preferably constructed of brass or other heat transmitting metal and is rigidly secured upon a bracket 8, of a similar metal. This bracket has an angularly depending portion 80 9, forming one end of the heat generating unit which, when actuated to generate heat, will transmit the heat so generated through the bracket to the shaft and melt the solder, allowing the sleeve 6 to be rotated about the 85 shaft 7.

The heat generating unit is preferably composed of a series of loosely mounted graphite disks 10 arranged one upon another in a cylinder 11 of lavite or other electric 90 insulating material with the disc at one end bearing against the heat transmitting bracket 9, and the other end bearing against a movable block 12, held in place and movable in the lavite cylinder. Three posts 13 secure the 95 heat transmitting bracket 9 to a closure plate 14 beyond the movable block. A sheet of mica or other electric insulating material capable of transmitting heat is interposed between the series of graphite disks and heat 100 transmitting bracket and between the series of graphite disks the movable block. The closure plate 14 supported on the posts 13 extending from the heat transmitting bracket is provided with an aperture 15 concentric 105 with the graphite disks 10 in which aperture is mounted a sleeve 16 having an outstanding flange 17 about its exterior end.

The interior of the sleeve is screw-threaded and adapted to register with a similarly 110 screw-threaded aperture in the movable block 12. A similarly screw-threaded pivot

18 having a flat head or button 19 is threaded through the sleeve and into the block securing the two together whereby the movement of the block limited by the plate 14 in one direction and by the sleeve flange 17 in the other direction. The heat transmitting bracket is carried upon and insulated from an outstanding arm 20 of a supporting plate 21 secured to the rear of the instrument casing. Upon this plate 21 below the graphite disks a pressure applying member 22 is pivotally mounted having a portion 23 adapted to contact with the flat head or button 19 upon the screw threaded shaft engaging the movable block contacting with the graphite disks and having an extension 24 spacing between two posts 25 extending from the supporting plate 21 which posts limit the movement of the member 22 to and from said shaft 18.

A Bourdon or pressure tube 26 is preferably secured to the casing below the supporting plate 21 in any desired manner having a connection 27 extending through the casing, connecting with the interior of the Bourdon tube and adapted to be secured to a tube 28 leading therefrom to a heat coil or bulb 29 adapted to be secured within the stack 30 leading from the furnace to the chimney or otherwise located so that the heat generated in the furnace by the flame from the electrically operated oil burner mechanism will cause an expansible gas or liquid within the bulb 29, tube 28 and Bourdon tube 26 to exert and vary the pressure therein causing the Bourdon tube to expand or contract.

The free end of the Bourdon tube 26 is pivotally connected by an operating link 40 to the pressure applying member 22, preferably with an adjustable connection thereto, such as the slot illustrated, so that upon the expansion of the Bourdon tube pressure will be applied to the series of graphite disks, the amount of pressure and the time of application of the pressure being regulated by the distance between the head or button 19 upon the shaft and the sleeve flange 17 by the screwing or unscrewing of the threaded portion of the shaft 18 into the movable block 12.

It is preferable to construct the operating link of two parts having a slidable frictional engagement with the other, such as by providing one part 31 with a reduced portion 32 adapted to be received and slide within a recessed portion 33 of the other member 34 having said recessed portion cut out on one side adapted to receive a spring 60 pressed clamping member 35 to bear with adjustable tension upon the reduced portion of the other member sliding within the recess, whereby an outward movement of the free end of the Bourdon tube, as the Bourdon tube expands, will be transmitted

through the operating link to cause the pressure applying member 22 to move about its pivot and apply pressure upon the shaft 18 and thence through the movable block 12 to compress the graphite disks 10 and when 70 further movement of the shaft is limited by the flange 17 on the sleeve engaging the plate 14 and extension 22 stopping on lower limiting post 25, further movement of the free end of the Bourdon tube will cause the 75 reduced end portion 32 of the operating link to overcome the tension of the clamping member 35 and slide within the recess 33 of the other member, so that as soon as the Bourdon tube begins to contract causing an 80 inward movement of its free end this inward movement will be instantly transmitted to the pressure applying member 22 causing it to tilt in the opposite direction and relieve the pressure from the series of graphite 85 disks until the extension 24 engages one of the limiting posts 25 and upon continued contraction of the Bourdon tube causing continued inward movement of the free end thereof the reduced portion of one member 90 of the operating link will be caused to overcome the frictional engagement with the clamp and slide within the recess of the other member, whereby expansion of the Bourdon tube at any time will immediately 95 apply pressure to the graphite disks.

The pawl 4, normally engaging the ratchet wheel 5 is so constructed that a pressure against the pawl in the direction of the back of the casing will cause it to disengage from the ratchet and thereby allow the counterweight 3 to tilt the mercury tube into the open position and break the circuit therethrough. A pawl releasing means is provided in this device which will break the circuit as the expansion of the Bourdon tube reaches its danger limit and this means comprises an arm 36 pivoted at one end to the free end of the Bourdon tube which passes over the horizontal portion of the pawl 4 110 when engaging the ratchet wheel and is provided with an angular depending portion 37 adapted as the Bourdon tube approaches its danger limit, to engage and depress the pawl 4 to release it from the ratchet 5 and allow the counterweight to break the circuit. The free end of the pawl releasing member 36 is provided with an irregular slot 38 adapted to slide over a pin 39 to support the arm 36 with the depending portion thereof out of contact with the pawl during the normal operation of the Bourdon tube, but from the shape of the slot 38 adapted to present the depending portion 37 first into line and then into engagement with the pawl 4 115 as the Bourdon tube approaches the danger limit.

The instrument casing is provided with three binding posts the upper binding post 40 being connected to a lead 41 from the 130

commercial source of current and to one terminal of the mercury tube switch. The other terminal of the mercury tube switch is connected to the middle binding post 42 which in turn is connected by a lead 43 to one of the outermost graphite disks 10 of the series. The other outermost graphite disk of the series is connected by a lead 44 to the lowermost binding post 45 which in turn is connected to one pole of the electric motor M for operating the burner mechanism and the other pole of the motor is connected to the other lead 46 of the commercial current.

15 In the electrical art it is recognized that a series of graphite disks such as shown and described will transmit electricity and generate heat in proportion to the amount of pressure applied to the end of such series 20 of disks, the greater the pressure, the greater the conductivity or ease with which the current passes through the series, as increasing the pressure upon the series of disks decreases the electrical resistance therethrough 25 and the heat generated by the resistance varies in direct proportion thereto. By a proper adjustment of the relation between the movable plate 12 and the screw-threaded shaft 18 an amount of pressure can be normally applied to the series of graphite disks 30 to generate heat sufficient to melt the solder normally securing the ratchet wheel 5 in fixed relation to the fixed shaft 7 and by providing a proper number of graphite disks 35 sufficient pressure may be applied thereto by normal movement of the member 22 upon expansion of the Bourdon tube 26 to allow the current to pass through the disks without generating sufficient heat to melt the solder. The instrument is so adjusted that with the switch in closed position, as shown in Figure 1, and the circuit through the motor closed, the current will pass through the 40 series of graphite disks 10 which are so adjusted that a continuation of the passage of current will generate sufficient heat to melt the solder and release the switch to be operated by the counterweight 3 to break the circuit. The parts are also adjusted so that as soon as the motor starts the oil burner mechanism operating, the flame therefrom or the heat arising from the fire box acting upon the bulb or coil 29 will cause an expansion of the Bourdon tube 26 thus applying pressure through the link and pressure applying member to the series of graphite disks reducing the generation of heat therein and the parts are further adjusted so that 45 the normal expansion of the Bourdon tube under these conditions will cause the flange 17 upon the sleeve to engage the plate 14 when the current passes freely through the compressed graphite disks without generating sufficient heat to melt the solder. A

further expansion of the Bourdon tube will be accommodated by the frictional engagement of the two sections 31 and 34 of the connecting link without further movement of the pressure applying member. Upon the failure of the burner flame from any cause the contraction of the Bourdon tube will immediately release the pressure from the graphite disks thereby immediately increasing the heat generated therein to melt the solder and release the switch to assume the open position. If from any cause the amount of pressure within the Bourdon tube approaches its danger limit, the sliding member 37 will engage the pawl and release it from the ratchet and allow the counterweight to break the circuit.

From the above description it is seen that this device includes a double safety device both of which depend upon the operation of the oil burner mechanism. The first safety device is operated by the commercial source of current passing therethrough causing the circuit to be broken in case the burner flame fails to ignite or becomes extinguished for any reason. The second safety device will operate if the burner mechanism produces excessive pressure within the Bourdon tube causing it to expand and approach this danger limit to release the pawl and allow the counterweight to throw the switch to break the electric circuit.

I claim:

1. In a pressure actuated electric control, 100 an electric switch, means normally acting to hold the switch in open position, detachable means for holding the switch in closed position, an operating member therefor in circuit with the switch and operable by variations in current passing therethrough to release said switch holding means, an expandable and contractable member, means actuated thereby to cause variations in the current passing through the operating member 105 of the switch holding means, and additional means operable thereby to mechanically detach said switch holding means.

2. In a pressure actuated electric control, 115 an electric switch, means normally acting to hold the switch in open position, detachable means for holding the switch in closed position releasable mechanically and upon the application of heat, an electric heat generating means in circuit with said switch, 120 an expandable and contractable member, means actuated thereby adapted to produce variations in the heat generated by the electric means to hold or release the detachable means, an additional means actuated at a predetermined expansion thereof to operate said mechanical releasing means.

3. In a pressure actuated electric control, 125 an electric switch, means normally acting to hold the switch in open position, detachable

- means for holding the switch in closed position releasable mechanically and independently upon application of heat, pressure controlled electric heat generating
- 5 means in circuit with the switch, an expansible and contractable member, means associated with said member and said heat generating means for transmitting pressure upon expansion and contraction of said
- 10 member to said heat generating means for controlling generation of heat thereby, and independent means operable at a predetermined expansion of said member to release said switch holding means.
- 15 4. In a pressure actuated electric control, an electric switch, means normally acting to hold the switch in open position, detachable means holding the switch in closed position releasable mechanically and independently
- 20 upon the application of heat, pressure controlled electric heat generating means in circuit with the switch, an expansible and contractable member, means operable upon the expansion and contraction of said member to transmit variations in pressure to said electric heat generating means to vary the degree of heat generated thereby and at predetermined expansion of said expansible and contractable means to reduce
- 25 30 the amount of heat generated by said elec-

tric means, and at a predetermined greater expansion to mechanically release said switch holding means.

5. In a pressure actuated electric control, an electric switch, means normally acting 35 to hold the switch in open position, detachable means for holding the switch in closed position, said means adapted to release the switch by mechanical operation and additionally by the application of heat, pressure 40 controlled electric heat generating means in circuit with the switch adapted to release said detachable switch holding means, a pressure actuated expansible and contractable member, means for applying pressure 45 therefrom to said pressure control electric heat generating means, a connection between said means and said expansible and contractable member normally allowing said electric means to generate sufficient degree 50 of heat to detach said switch and upon expansion of said expansible and contractable member to apply pressure to said electric heat generating means to reduce the degree of heat therebelow, and means operable 55 upon abnormal expansion of said expansible and contractable member to operate said mechanical means to release said switch holding means.

IRA E. McCABE.
